UNITED STATES PATENT OFFICE.

SION D. RICH, OF AVOCA, TEXAS, ASSIGNOR OF ONE-FOURTH TO LUDDIE CROMPTON,
OF AVOCA, TEXAS.

RAILWAY-CAR COUPLING.

1,002,178.

Specification of Letters Patent. Patented Aug. 29, 1911.

Application filed December 18, 1909. Serial No. 533,787.

To all whom it may concern:

Be it known that I, SION D. RICH, a citizen of the United States, residing at Avoca, in the county of Jones and State of Texas, have invented a new and useful Railway-Car Coupler, of which the following is a specification:

My invention relates to car couplings and has for its object the provision of a simple and efficient device by which the train pipe and the cars will be coupled together.

The invention consists in certain novel features of the device illustrated in the accompanying drawings, all of which will be hereinafter, first, fully described and then particularly pointed out in the appended claim.

In the drawings, —Figure 1 is a horizontal section of a coupling embodying my invention. Fig. 2 is an elevation, partly broken away, of one draw head. Fig. 3 is a central longitudinal section of a draw head. Fig. 4 is a detail perspective view of the pin lifter.

My coupling comprises a pair of draw-heads 1 which may be secured to the under side of the car body or platform in the usual manner and each draw head is provided with a central longitudinal recess or chamber 2 and a passage 3 leading rearward and downward from the said chamber or recess in which the train pipe 4 is fitted. To the end of the train pipe, I secure a coupling head 5 of rubber or similar material which is provided with an annular shoulder 6 on its inner side, as clearly shown. A spring 7 is coiled around the train pipe and the said head 5 between the annular shoulder 6 and the end of the recess or chamber 2 and serves to project the said coupling head forward so that when two draw heads are brought together the heads 5 will be held in contact with each other so forcibly as to form an air tight joint. In order to prevent rotation of one of the coupling heads upon the other the heads are provided with interlocking projections or spurs 8, as shown.

At the opposite sides of the central recess or chamber 2 each draw head is provided with chambers 9 and 10 in one of which a hook 11 is pivoted at 9^a and in the other of which a knuckle or coupling head 12 is pivoted at 10^a. The chambers 9 and 10 of the draw heads are reversely arranged so that

when the draw heads are brought together the hook 11 of each draw head will enter the chamber 10 of the meeting draw head and engage the knuckle 12 therein. The chambers are formed with their inner walls 19 flat and equidistant from the transverse center of the draw heads whereby they are adapted to align with each other, and when two heads are brought together and the hooks engage with the knuckles, each hook 65 is caught between said wall and knuckle of the mating draw head as shown in full lines 68 in Fig. 1. The knuckle is constructed with a coupling point 12^a adapted to engage the lip or point 11^a of the hook 11 and in rear 70 of the pivotal connection of the knuckle it has a projection or cam face 13 for a purpose to appear below. A coil spring 14 is mounted within the chamber 10 so as to bear on the said knuckle and force the inner 75 end thereof toward the inner wall and the outer end against the outer wall of the chamber or recess in which it is located so that it will lie normally in the uncoupled 80 position, as shown in dotted lines in Fig. 1. The front end of the knuckle is provided at its outer side with a spur 15 upon which a locking pin 16 is adapted to rest when the parts are uncoupled. When the two draw-heads are brought together, the hooks 11 85 will pass into the chambers 10 and striking against the inner projecting portions 13 of the knuckles will swing the knuckles on their pivots in opposition to the springs 14 whereupon the front ends 12^a of the 90 knuckles will be swung into engagement with the lips 11^a of the hooks so as to prevent the withdrawal of the hooks and the same motion of the knuckles will carry them from under the locking pins 16 so that the said pins will at once drop into 95 position in rear of the spurs 15 and against the same, as shown in Fig. 1, and thereby hold the parts in their coupled position, as will be readily understood.

The locking pin 16 is provided with lugs or off-sets 17 adapted to bear upon the upper side of the draw head and thereby prevent the pin dropping so far into the draw head as to carry it beyond its proper engagement with the knuckle or to injure the bottom of the draw head in any way. Near the upper end of the pin is a forwardly projecting arm 18 the purpose of which will presently appear. Upon the end of the car 110

body or the car platform, I journal a pin lifter consisting of a rock shaft 20 having downturned ends or handles 21 and provided between its ends with lifting arms 22 and 23 which are of unequal length. The arm 22 is provided with a chain 24 which is attached to the locking pin 16 in the draw head immediately under the pin lifter while the opposite arm 23 is provided with an off-set end 25 which is adapted to engage under the arm 18 on the locking pin in the meeting draw head. When it is desired to uncouple the cars the handles 21 are swung upward and forward thereby causing the lifting arms 22 to swing upward and consequently raising the locking pins so that the cars may be readily pulled apart, the arm 18 riding over and out of engagement with the off-set 25 of the arm 23, as will be readily understood.

From the foregoing description, taken in connection with the accompanying drawings, it will be seen that I have provided a coupling of very simple construction by which a single operation will effectually couple the cars and also connect the ends of the train pipe. The construction is such that the parts will be securely held together when coupled so that accidental uncoupling of the cars or breaking of the train pipe connection will be effectually avoided. The locking pins 16 are preferably provided

with angular faces in their lower portions so as to bear firmly against the sides of the knuckles and thereby positively prevent the uncoupling movement of the same during running of the train.

Having thus described my invention what I claim is:

The combination of a combined car and train pipe coupler comprising a draw head provided with three horizontally disposed recesses, coupling members located in the two outer recesses, said members being adapted to engage with corresponding devices on a co-acting coupler head to hold said heads in rigid alinement, a gasket having a reduced inner end mounted in the intermediate recess and provided with a central bore, a connection between said gasket and the train pipe, and a spring surrounding the inner end of said gasket and adapted to press said gasket against a corresponding gasket of the other coupler to make an air tight joint therewith when the coupler heads are interlocked together.

In testimony that I claim the foregoing as my own, I have hereto affixed my signature in the presence of two witnesses.

SION D. RICH.
